UNITED STATES PATENT OFFICE.

PLIN C. SOUTHWICK, OF SANDWICH, ILLINOIS.

BALING-PRESS.

SPECIFICATION forming part of Letters Patent No. 792,359, dated June 13, 1905.

Application filed January 23, 1904. Serial No. 190,372.

To all whom it may concern:

Be it known that I, PLIN C. SOUTHWICK, a citizen of the United States, and a resident of Sandwich, county of Dekalb, and State of Illinois, have invented certain new and useful Improvements in Baling-Presses, of which the following is a specification and which are illustrated in the accompanying drawings, forming a part thereof.

10 The invention relates to that type of baling-presses for operating upon hay and like material in which there is provided a chest having a top feed-opening for receiving the material and in connection with which there 15 are used division or spacing blocks for separating the bales as they are formed.

The invention relates particularly to means for introducing the blocks into the feed-opening; and it consists of the mechanism herein- 20 after described and claimed and which is illustrated in the accompanying drawings, in which—

Figure 1 is a detail side elevation of a baling-press of the type referred to, the details 25 of the operating mechanism, however, being omitted. Fig. 2 is a detail plan of the chest of the press, and Fig. 3 shows the block-carrier in perspective.

The body or chest of the press is indicated 30 at 10 and has the upper longitudinal side rails 11 12. The usual oscillating feeder is shown at 13 for forcing the charge down into the feed-opening Z, and the division-blocks are shown at 14, one within the compression-chamber of the press and located between a completed bale X and a forming bale Y and one 35 fixed within the block-carrier, so that it may be dropped within the feed-opening Z when required.

40 Brackets 15 15 are fixed one at each side of the chest and secured to the top rails 11 12, these brackets being alike and each having a vertical socket for receiving the shaft 16, upon which the hinge-plates 17 of the carrier 18 45 may be journaled. To the face of the carrier there is attached a pair of Z-plates 19 20, these plates being positioned one adjacent to each side edge of the carrier, and their outer flanges

project inwardly or toward each other, thereby forming ways for receiving the block 14. 50

A platform 21 is mounted on top of the chest of the press adjacent to the feed-opening Z, the width of this platform being substantially identical with that of the chest, and extension-blocks 22 23 project laterally as to the 55 chest, their upper faces being flush with the top of the platform, these blocks serving as supports for the block 14 when held in the ways of the carrier, the carrier being swung to the side of the press. 60

In order to drop the block 14 into the feed-opening, the carrier is swung forwardly across the platform 21 until the block is carried beyond its edge and over the feed-opening, when it drops by gravity. Should the fall of the 65 block be resisted by the material within the chest, it is forced downwardly by means of a lug 24 upon the front end of the feeder 13, and in order that this lug may not mutilate the carrier the latter is provided with a vertical recess 25, through which the lug may descend. 70

The ways formed by the Z-plates 19 20 being open at the top and bottom, the carrier is reversible from side to side of the press. As 75 shown, it is intended to fit loosely upon the shaft 16, and when it is desired to shift the carrier from one side to the other of the press it is removed from the shaft, and the shaft is then transferred from the one bracket 15 to 80 the other and secured within its socket, when the carrier is overturned and its hinges again fitted upon the shaft. This transferring of the carrier from side to side of the press is important for the reason that the press may 85 be fed from either side, and it is desirable that the carrier should be located upon the opposite side from that upon which the operator stands in order that it may be out of his way.

The brackets 15 are extended outwardly, as 90 shown, and the extension-blocks 22 23 are employed in order that the carrier may be swung completely to the side of the press, so as not to interfere with the feeding operation. When a block is to be dropped, the carrier is swung 95 forwardly either by hand or by the use of a

fork which the operator will invariably have in his hand. After one block has been dropped the carrier is swung back to the side of the press, and another one may be inserted by an attendant.

In order to prevent the dropper from swinging too far forwardly, the hinge-plates 18 are provided with lugs 26, adapted to engage a stop-lug 27, projecting outwardly from the bracket 15.

I claim as my invention—

1. In a baling-press, in combination, a chest having a top feed-opening, a platform adja-

cent the opening, a block-carrier pivoted at the side of the chest and adjacent the aperture and platform and oscillating over the latter.

2. In a baling-press, in combination, a chest having a feed-opening; an oscillatory block-carrier mounted on the chest adjacent the opening; and a track formed on top of the chest on which the block held by the carrier may slide.

PLIN C. SOUTHWICK.
